US00D807497S

(12) **United States Design Patent** (10) Patent No.: **US D807,497 S**
(45) Date of Patent: **** Jan. 9, 2018**

(54) **PAD FOR FOREHEAD SUPPORT**

(71) Applicant: **ResMed Limited**, Bella Vista, New South Wales (AU)

(72) Inventor: **Philip Rodney Kwok**, Sydney (AU)

(73) Assignee: **ResMed Limited**, Bella Vista (AU)

(**) Term: **15 Years**

(21) Appl. No.: **29/594,560**

(22) Filed: **Feb. 21, 2017**

Related U.S. Application Data

(60) Division of application No. 29/496,315, filed on Jul. 11, 2014, now Pat. No. Des. 782,028, which is a continuation of application No. 12/980,821, filed on Dec. 29, 2010, now Pat. No. 9,220,861, which is a continuation of application No. 11/207,006, filed on Aug. 19, 2005, now Pat. No. 7,882,837, which is a continuation of application No. 10/661,570, filed on Sep. 15, 2003, now Pat. No. 6,997,188, which is a continuation of application No. 10/230,169, filed on Aug. 29, 2002, now Pat. No. 6,691,708, which is a division of application No. 09/608,440, filed on Jun. 30, 2000, now Pat. No. 6,463,931, which is a continuation of application No. 09/008,708, filed on Jan. 16, 1998, now Pat. No. 6,119,693.

(57) **CLAIM**

The ornamental design for a pad for forehead support, as shown and described.

DESCRIPTION

FIG. 1 is a front isometric view of a pad for forehead support according to my new design;

FIG. 2 is a reverse isometric view thereof;

FIG. 3 is another front isometric view thereof;

FIG. 4 is a top view thereof; and,

FIG. 5 is an end view thereof.

1 Claim, 2 Drawing Sheets
